UNITED STATES PATENT OFFICE

2,280,651

THERMOSTAT

Carl G. Kronmiller, Minneapolis, Minn., assignor
to Minneapolis-Honeywell Regulator Company,
Minneapolis, Minn., a corporation of Delaware

Application April 19, 1937, Serial No. 137,725

24 Claims. (Cl. 200—139)

This invention relates to thermostats and more particularly to a thermostatic structure embodying a timed operating mechanism and provided with means to shift the control of the instrument from a predetermined day temperature to a predetermined night temperature.

A primary object of this invention is the provision of an improved thermostatic switching mechanism provided with a day-night shift embodying improved means for providing a change from day to night temperatures and vice versa at predetermined times.

An additional object is the provision of means in such a mechanism whereby the day temperature controls the mechanism actuated by the instrument unless the timed mechanism in association with the device is in operative position.

A further object is the provision of such a mechanism whereby unless the setting of the night temperature indicator is below that of the day temperature indicator the day temperature will control in such manner that the night setting may never be higher than the day setting.

An additional object is the provision in a structure to be hereinafter described of means whereby the day and night temperatures may be predetermined independently of each other and the instrument readily adjusted to operate the controlled mechanism at such temperatures.

As conducive to a clearer understanding of this invention, it may here be pointed out that in numerous temperature or other condition controlling installations it is desirable that thermostatic means be provided to control a source of heat, such as a burner or furnace, in such manner that during the night, or during such period of time as the occupants are out of the dwelling or other building, it is desirable that the temperature be reduced to a lower level than during the day or during such periods of time as the structure is occupied. For various reasons, such as economy, it is sometimes undesirable that a continuously operating clock thermostat be provided. In such cases it is advantageous to have a thermostat of relatively simple and inexpensive construction having timed means associated therewith whereby the temperature may be reduced from a given setting to a relatively lower setting for a desired period, at the termination of which period the setting will return to the previously mentioned higher temperature.

One object of this invention is the provision of an improved thermostat of the above mentioned character provided with timed mechanism whereby the temperature may be reduced for any

given period within the scope of the operating range of the instrument and thereafter automatically returned to a higher temperature. In such instruments it is desirable that both the lower and higher temperatures may be readily varied but it is undesirable that the normal lower temperature should ever be in excess of the normal higher temperature, whereby upon the operation of the instrument in such a manner that the lower temperature should take control actually a higher temperature will prevail.

It is a further object of this invention to preclude such a contingency.

A still further object is the provision of such a mechanism which will be simple of construction, readily operable by unskilled persons and sturdy and durable in construction.

Other objects will in part be obvious and in part pointed out hereinafter.

20 The invention, accordingly, consists in the combinations of elements, arrangements of parts and features of construction all as will be more fully pointed out hereinafter and disclosed in the accompanying drawing.

25 Referring now to the accompanying drawing wherein an illustrative embodiment of the inventive concept is disclosed:

Figure 1 is a front elevational view of a structure embodying the instant invention showing 30 the cover in position and various external operating mechanism;

Figure 2 is an enlarged front elevational view of the device with the cover and certain other parts removed for the sake of clarity;

35 Figure 3 is an enlarged side sectional elevational view taken along the line 3—3 of Figure 1 as viewed from the left;

Figure 4 is a sectional view taken along the line 4—4 of Figure 2 as viewed from the bottom;

40 Figure 5 is a sectional view taken along the line 5—5 of Figure 2 as viewed from the top;

Figure 6 is a sectional view taken along the line 6—6 of Figure 2 as viewed from the left; and

45 Figure 7 is a bottom elevational view of portions of the structure shown in Figure 2.

Similar reference characters denote similar parts throughout the several views of the drawing.

50 Referring now to the drawing in detail and more particularly to Figure 3, a mounting plate generally indicated at 10 is secured to a wall or other suitable surface (not shown) as by screws or in any other desired manner. A base plate 11 which, in turn, carries the operating

mechanism is secured as by screws 12a, 12b and 12c (see Figure 2) to mounting plate 10. For a more complete description of mounting plate 10 and the advantages achieved thereby and the use thereof, reference is made to the co-pending application of Carl G. Kronmiller and Homer E. Malone, Serial No. 55,603, now Patent No. 2,171,272, filed December 21, 1935, entitled "Condition responsive switch" and assigned to the same assignee. For the purposes of the instant case, it is sufficient to say that the use of the mounting plate 10 precludes the possibility of distortion of base plate 11 by excessive tightening of the fastening means.

Base plate 11 has mounted thereon a casing 14 as by screws 15, which casing contains a clock mechanism (not shown) which may be of any suitable type but preferably contains those embodiments disclosed in the co-pending application of Andrew G. McNicoll Serial No. 98,288, now Patent No. 2,108,776, filed August 28, 1936, entitled "Starting mechanism" and assigned to the same assignee. The clock mechanism is provided with a winding stem 16 adapted to be rotated in a manner to be described hereinafter to tension the mechanism to rotate for a predetermined time period, which in the illustrative embodiment herein shown will be in the neighborhood of 11 or 12 hours, and includes a slip friction mechanism as disclosed in the above mentioned McNicoll application for a purpose to be later pointed out.

Resiliently mounted on winding stem 16 in a manner to be described hereinafter is a lever 17, the distal end of which is positioned for abutment with an end 18 of a lever 19 mounted on a pivot 20. Lever 19 is connected as by a link 25 and a pin 26 to an inwardly turned portion 27 of a U-shaped bimetallic element 28 through a rivet 29. Bimetallic element 28 is provided with an extending bracket 30, as better shown in Figure 4, having inwardly turned apertured portions positioned adjacent a second bracket 31 also provided with registering apertured portions similar to bracket 30. A pivot pin 32 passed through the registering apertures thus permits pivotal movement of bimetallic element 28. A spring 33 one end of which engages a suitable aperture 34 in bracket 31 and a second aperture 35 in bimetallic element 28 normally biases bimetallic element 28 in a counter-clockwise direction as viewed in Figure 2 about pivot 32.

Mounted and secured as by rivets 40 on either side of base plate 11 is a pair of insulating panels 41 and 42. Bracket 31 is secured to insulating panel 41 in such a manner that it is electrically insulated from base plate 11 for a purpose to be hereinafter set forth. Bracket 31 has an extending portion 45 which is in electrical association with screw 12a which, in turn, extends to a suitable terminal (not shown) in mounting plate 10.

The opposite end of bimetallic element 28 carries a member 46 which is, in turn, provided with a contact button 47. Contact button 47 is adapted when in one position to engage a contact 49 carried by an arm 50 in electrical association, through an extending portion 51 with screw 12b, which, in turn, is electrically associated with a second terminal carried by mounting plate 10. When in its other position contact button 47 is adapted to engage a contact 52 carried by an arm 53 in electrical association, through a member 54 with screw 12c, which, in

turn, is electrically associated with a third terminal carried by mounting plate 10. Suitable screws 55 secure member 51 in insulated relationship with base plate 11 as shown in Figure 5, and corresponding screws 56 secure member 54 in a similar manner.

A U-shaped insulating bracket 60 is secured as by a rivet 61 to member 53 and positioned, as better shown in Figure 5, so that the extending portions of the U are located on opposite sides of member 46 to prevent displacement of member 46 and consequently contact 47 from its normal alignment with contacts 49 and 52. Means are also provided whereby the position of contact button 52 may be varied to change the operating differential of the instrument in a known manner. Such means comprise an internally and exteriorly threaded member 62 engaging a threaded aperture in member 53 and having a screw 62a threaded therein, screw 62a carrying contact button 52. Threaded member 62 is provided with a dial 63 carrying suitable indicia thereon. A pointer 64 comprises an integral portion of member 53 and the adjustment of dial 63 with respect to pointer 64 indicates the relative position of contact 52 and hence the operating differential of the instrument. Screw 62a may be independently rotated and sealed during manufacture to provide factory calibration.

It may here be pointed out that a wire 70 leads from a terminal 71 on member 54 to a resistance element 72 carried by a receptacle 73 in electrical association with bracket 31 and hence screw 12a and its associated terminal, the purpose of which resistance element is primarily to impart an artificial increase in temperature to the space adjacent bimetallic element 28 in a known manner and for a known purpose in order that the movement thereof may be accelerated under certain conditions.

Lever 19 at an end 75 opposite end 18 carries an extending portion 76 provided with a threaded aperture in which is positioned a screw 77 adapted to abut, under certain circumstances to be hereinafter described, a cam 78 secured for rotation as by a nut 79 upon a shaft 80 mounted within a sleeve 81 (see Figure 6). The opposite end of shaft 80 is rigidly secured as by a rivet 80a to a dial 82 carrying indicia on the face thereof and having an arcuate slot 83 extending about a circumferential portion thereof. A member 84 secured in any suitable manner to insulating plate 42 has an inwardly turned portion 85 extending into slot 83 and serves as a stop to limit rotation of dial 82 and hence cam 78. An extending portion 86 of base plate 11 is curved inwardly to provide a pointer adjacent the indicia carried by dial 82.

It should here be pointed out that sleeve 81 is rigidly and non-rotatably secured to base plate 11. A second sleeve 88 surrounds sleeve 81 and is provided with a cam 91 which may be integral therewith. Rigidly secured to sleeve 88 is a second dial 92 also bearing indicia thereon but of smaller circumference than dial 82. Dial 92 is also provided with an arcuate slot 93 into which projects an end 94 of a member 95 suitably secured to insulating plate 41, the abutment of member 95 with the ends of slot 93 serving as a stop to limit the rotation of dial 92. A second lever 96 is carried by pivot 20 but is curved outwardly adjacent an end 97 in such a manner that the combined ends 75 of lever 19 and 97 of lever 96 comprise a Y. The end 97 is provided with an up-turned portion 98 having

a threaded aperture therein through which projects a screw 99 similar to screw 77 but positioned for abutment with cam 91. A spring 100 extends between portions 98 of lever 96 and 78 of lever 19 for a purpose to be described more fully hereinafter. Means are also provided for holding the dial 82 rigidly in any of its adjusted positions, such means taking the form of a screw 101 and a friction plate 101a adapted to abut dial 82 and by the pressure exerted thereagainst hold the same from rotation.

Referring again to lever 17, it will be seen that the same is provided with a U-shaped portion generally indicated at 102 (see Figure 7) and comprising a pair of substantially parallel apertured portions 103 and 104 which encircle winding stem 16 of clockworks 14 and are freely rotatable thereabout. The center 105 of the U-shaped member 102 is provided with a slotted aperture 106 through which is passed a screw 107 engaging winding stem 16. A coil spring member 108 has one end secured about screw 107 and the other end engaging in a suitable aperture 109 in lever 17, spring 108 being so arranged as to bias lever 17 in a direction towards end 18 of lever 19. Thus it will be seen that the spring 108 in combination with slot 106 and screw 107 serves as a strain release permitting a relatively slight rotation of winding stem 16 with respect thereto and similarly a relatively slight rotative movement of lever 17 with respect to winding stem 16.

Now from the foregoing it should appear that when lever 17 is in the position as shown in Figure 2 in abutting relation with end 18 of lever 19, end 75 of lever 19 and, correspondingly, screw 77 will be biased into abutting relationship with cam 78 and that rotation of cam 78 will vary the position of lever 19 since the previously described strain release will permit such limited motion as may be imparted thereto by adjustment of the cam. It will likewise be seen that such motion of lever 19 will be imparted through link 25 and pivots 26 and 28 to bimetallic element 28 and consequently to contact button 47 moving the same towards one or the other of contacts 52 or 49. It will further be seen, however, that as the lever 17 is moved away from the end 18 of lever 19 the lever will be free to move in response to pressure exerted thereon through bimetallic element 28, which pressure is imparted thereto by spring 33, in such a manner that screw 77 may move away from its associated cam 78 and screw 99 move towards its associated cam 91, and that under such circumstances movement imparted to dial 92 will be transmitted through lever 97 to lever 19 and hence to bimetallic element 28. It should here be pointed out that spring 100 is of greater strength than spring 33 and that hence in the absence of pressure imparted by lever 17 to the end 18 of lever 19 movement imparted to screw 99 by cam 91 is directly imparted to bimetallic element 28 since the levers 96 and 19 when in the relationship above mentioned provide substantially an integral unit. It will further be seen, however, that the cams 78 and 91 are so positioned and arranged that when dial 82 is adjusted to a temperature of, illustratively, 60° should cam 91 be adjusted by dial 92 to a temperature of, illustratively, 70° the radius of cam 78 with respect to the radius of cam 91 is such that screw 77 will be brought into abutting relationship therewith and spring

100 will thereupon yield in such a manner that the temperature of the day setting, namely 60°, will be the controlling temperature of the instrument.

Referring again to winding stem 16, it will be seen, as best shown in Figure 3, that a sleeve 110 is positioned thereabout and held in position thereon as by a set screw 111. A resilient collar 112 is positioned upon a shoulder of sleeve 110, which sleeve frictionally engages a dial 113 bearing indicia thereon. This indicia is visible through an aperture 114 in a casing 115 which normally encloses the mechanism previously described. A portion of aperture 114 is formed into a pointer 116. Secured to dial 113 as by pins 119 extending into suitable apertures therein is a sleeve 120 provided with a knurled portion 121 which extends exteriorly of the casing. An operating handle 122 is rigidly secured to winding stem 16 as by a screw 123. A friction disc 124 is positioned between the lower surface of operating handle 122 and the upper surface of sleeve 120. Casing 115 is provided with suitable slots through which the upper peripheral portions of dials 82 and 92 as well as pointer 86 project. These slots in connection with a screw 126 engaging a suitable inwardly turned lug 127 of base plate 11 serve to hold the casing and its associated mechanism in related assembly. Casing 115 is also provided with graduations indicative of temperature degrees, and positioned interiorly of the casing and adjacent a slot 128 is a thermometer 129 which may be held in place in any suitable manner as by a vertically extending strip 130 engaging an inwardly turned portion 131 adjacent the lower portion of the casing and secured to a correspondingly inturned portion 132 in the upper portion of the casing as by a screw 133.

Suitable lead wires (not shown) are adapted to be directly connected to the terminals engaged by screws 12a, 12b, and 12c on base plate 10. These wires may lead to any suitable control apparatus such as an oil or gas burner, a stoker motor or a draft regulator or any other desired heating apparatus.

From the foregoing the operation of the device should now be apparent. Assuming that the device is set as shown in Figure 2 to operate at a day temperature of 70° and a night temperature of 55°, which settings may be readily varied, as will be appreciated, by rotation of the dials 82 and 92, and the occupant upon retiring desires that the night temperature become effective for a period of, illustratively, 8 hours until a time, say one hour before rising. The occupant therefore need only rotate dial 113 until the highest number on the scale, which in the illustrative embodiment shown is 12, is adjacent pointer 116 and then rotate operating handle 122 which will wind the clock mechanism and simultaneously through friction disc 124 move dial 113 until the figure 8 is adjacent pointer 116. Such movement will position lever 17 a substantial distance from end 18 of lever 19, the distance gradually decreasing as the 8 hour period progresses and during the time that the lever 17 is out of engagement with end 18, assuming of course, as above discussed, that the night setting is below the day setting, the position of bimetallic element 28 will be determined by the position of screw 99 with respect to cam 91. At the termination of such operating period, the abutment of lever 17 with end 18 will cause a movement of lever 19 in a clockwise direction as viewed in

Figure 2 until such time as the screw 17 abuts its associated cam 18 whereupon the day temperature setting as determined by the position of cam 18 will again take effect. During either of such settings, the position of contact button 47 with respect to contact 52, which it should here be pointed out is the hot contact, or contact 49 which is the cold contact will be determined by the ambient temperature and its effect on bimetallic strip 28. Upon engagement of contact 47 with cold contact 49, a damper motor or analogous device will be energized to assume a position to effect an increase in temperature and upon engagement with the hot contact 52 a reverse operation will ensue. It should also be pointed out that if the occupant is leaving the house at, illustratively, three o'clock and desires that the temperature be reduced until, say five o'clock, planning to return at six, he need only rotate dial 113 to such a position that a number indicative of the time of day, in this instance 3, is adjacent pointer 116 and then rotate operating handle 122 until the number 5 indicative of the time at which he wishes the high temperature to again become effective is adjacent pointer 116 and the device will operate at night temperature until the hour designated by the last numeral juxtaposed to pointer 116. It should also be noted that if the operator imparts too much tension to the clock mechanism reverse rotation of handle 122 will relieve such tension through the slip friction mechanism previously mentioned whereby an accidental incorrect setting of the device may be remedied.

Thus from the foregoing, it will be seen that there is herein provided a device which accomplishes all of the objects set forth hereinbefore and others in an improved manner including many advantages of great practical utility.

As many embodiments may be made of the hereinbefore described invention and as many modifications may be made of the embodiment described, it is to be understood that all matter described or shown in the accompanying drawing is to be interpreted as illustrative and not in a limiting sense.

I claim:

1. In a device of the character described, in combination, a condition responsive element, condition control means operative by said element, first means for varying the position of said condition responsive element to vary the value of the condition to which said condition responsive element responds, second means for varying the position of said condition responsive element to vary the value of the condition to which said condition responsive element responds, timed means to render one of said position varying means inoperative for a predetermined period, and means for varying the duration of said period.

2. In a device of the character described, in combination, a condition responsive element, condition control means operative by said element, first means for varying the position of said condition responsive element to vary the value of the condition to which said condition responsive element responds, second means for varying the position of said condition responsive element to vary the value of the condition to which said condition responsive element responds, timed means to render one of said position varying means inoperative for a predetermined period, means for varying the duration of said period, and means including a numbered dial and a

pointer for indicating the duration of said period.

3. In a device of the character described, in combination, a condition responsive element, condition control means operative by said element, means for adjusting said condition responsive element to respond to a given value of a condition, second means for adjusting said condition responsive means to respond to a given value of a condition, means to render said first mentioned adjusting means inoperative for a predetermined period, and means precluding the operation of said condition control means by said second mentioned adjusting means when the said second means is set for a higher condition value than said first mentioned adjusting means.

4. In a device of the character described, in combination, a condition responsive element, condition control means operative by said element, a lever associated with said element, said lever comprising two members pivoted with respect to each other, resilient means normally biasing said members towards each other, a second resilient means biasing one of said members away from the other and stronger than said first mentioned resilient means, means for moving one of said members, and means for rendering said second resilient means ineffective for a predetermined period whereby said members may be moved as a unit.

5. In a device of the character described, in combination, a condition responsive element, condition control means operative by said element, a lever associated with said element, said lever comprising two members pivoted with respect to each other, resilient means normally biasing said members towards each other, a second resilient means biasing one of said members away from the other and stronger than said first mentioned resilient means, means for moving one of said members, means for rendering said second resilient means ineffective for a predetermined period whereby said members may be moved as a unit, and means for varying the duration of said predetermined period.

6. In a device of the character described, in combination, a condition responsive element, condition control means operative by said element, a lever associated with said element, said lever comprising two members pivoted with respect to each other, resilient means normally biasing said members towards each other, a second resilient means biasing one of said members away from the other and stronger than said first mentioned resilient means, means for moving one of said members, means for rendering said second resilient means ineffective for a predetermined period whereby said members may be moved as a unit, means for varying the duration of said predetermined period, and means visually indicating the duration of said predetermined period.

7. In a device of the character described, in combination, a condition responsive element, means operative by said condition responsive element to control the value of a condition, a timed mechanism, an abutment means associated with said timed mechanism for varying the position of said condition responsive element, said abutment means comprising a projection adapted when said timed mechanism is inoperative to hold said condition responsive element in one position and when said timed mechanism is operative to permit said condition responsive means to assume another position, means to vary the condition value to which said

condition responsive element responds when said timed mechanism is in operation, and second means to vary the value to which said condition responsive means responds when said timed mechanism is operative.

8. In a device of the character described, in combination, a condition responsive element, means operative by said condition responsive element to control the value of a condition, a timed mechanism, an abutment means associated with said timed mechanism for varying the position of said condition responsive element, said abutment means comprising a projection adapted when said timed mechanism is inoperative to hold said condition responsive element in one position and when said timed mechanism is operative to permit said condition responsive means to assume another position, means to vary the condition value to which said condition responsive element responds when said timed mechanism is inoperative, second means to vary the value to which said condition responsive means responds when said timed mechanism is operative, means for rendering said timed mechanism operative for a predetermined period and visual means for indicating the duration of said period.

9. In a device of the character described, in combination, a temperature responsive element, a timed mechanism, temperature control means operated by said element in response to variations in the value of a condition, means associated with said timed mechanism for changing the temperature value to which said element responds when said timing mechanism is operative, first means for predetermining the temperature value to which said element responds when said timed mechanism is inoperative, second means for predetermining the temperature value to which said element responds when said timed mechanism is operative, means for predetermining the duration of the operating period of said timed mechanism, and means precluding the operation of said temperature control means at the temperature value to which said second temperature value predetermining means is set when said last mentioned value is in excess of the setting of said first temperature value predetermining means.

10. In a device of the character described, in combination, a temperature responsive element, a timed mechanism, temperature control means operated by said element in response to variations in the value of a condition, means associated with said timed mechanism for changing the temperature value to which said element responds when said timing mechanism is operative, first means including a cam and a cam follower associated with said temperature responsive element for predetermining the temperature value to which said element responds when said timed mechanism is inoperative, second means including a cam and a cam follower associated with said temperature responsive element for predetermining the temperature value to which said element responds when said timed mechanism is operative, and resilient means associated with said temperature responsive element to hold said first mentioned cam follower in engagement with its associated cam when said timed mechanism is inoperative, and to move said second mentioned cam into engagement with its associated cam follower when said timed means is rendered operative.

11. In a device of the character described, in

combination, a temperature responsive element, a timed mechanism, temperature control means operated by said element in response to variations in the value of a condition, means associated with said timed mechanism for changing the temperature value to which said element responds when said timing mechanism is operative, first means including a cam and a cam follower associated with said temperature responsive element for predetermining the temperature value to which said element responds when said timed mechanism is inoperative, a second means including a cam and a cam follower associated with said temperature responsive element for predetermining the temperature value to which said element responds when said timed mechanism is operative, and resilient means associated with said temperature responsive element to hold said first mentioned cam follower in engagement with its associated cam when said timed mechanism is inoperative, and to move said second mentioned cam into engagement with its associated cam follower when said timed means is rendered operative, said cams being so arranged that if said second temperature value predetermining means is set at a higher value than the first temperature value predetermining means said temperature control means responds to the value at which said first temperature value means is set regardless of the operation of said timing means.

12. In a thermostatic switching mechanism, in combination, a bimetallic element, condition control mechanism operated by said element, a lever associated with said bimetallic element, said lever comprising two pivoted members, each provided with a cam follower, a pair of cams each adjacent one of said cam followers, a pair of dials, each fixedly associated with one of said cams, a pointer, indicia on said dials indicative of temperature values, rotation of said dials serving to vary the position of said cams in accordance with the temperature value adjacent said pointer, a timed mechanism, means associated with said timed mechanism to juxtapose one of said cam followers to its associated cam, whereby the position of said lever and hence said bimetallic element is determined by one of said cams when said timed mechanism is operative and the other of said cams when said timed mechanism is inoperative in such manner that said element responds to one temperature for the duration of the period of operation of said timed mechanism and another temperature value subsequent to the termination thereof.

13. In a thermostatic switching mechanism, in combination, a bimetallic element, condition control mechanism operated by said element, a lever associated with said bimetallic element, said lever comprising two pivoted members, each provided with a cam follower, a pair of cams each adjacent one of said cam followers, a pair of dials, each fixedly associated with one of said cams, a pointer, indicia on said dials indicative of temperature values, rotation of said dials serving to vary the position of said cams in accordance with the temperature value adjacent said pointer, a timed mechanism, means associated with said timed mechanism to juxtapose one of said cam followers to its associated cam, whereby the position of said lever and hence said bimetallic element is determined by one of said cams when said timed mechanism is operative and the other of said cams when said timed mechanism is inoperative in such manner that said element responds to one temperature for the duration of

the period of operation of said timed mechanism and another temperature value subsequent to the termination thereof, and means for varying the duration of the operating period of said timed mechanism.

14. In a thermostatic switching mechanism, in combination, a bimetallic element, condition control mechanism operated by said element, a lever associated with said bimetallic element, said lever comprising two pivoted members, each provided with a cam follower, a pair of cams each adjacent one of said cam followers, a pair of dials, each fixedly associated with one of said cams, a pointer, indicia on said dials indicative of temperature values, rotation of said dials serving to vary the position of said cams in accordance with the temperature value adjacent said pointer, a timed mechanism, means associated with said timed mechanism to juxtapose one of said cam followers to its associated cam, whereby the position of said lever and hence said bimetallic element is determined by one of said cams when said timed mechanism is operative and the other of said cams when said timed mechanism is inoperative in such manner that said element responds to one temperature for the duration of the period of operation of said timed mechanism and another temperature value subsequent to the termination thereof, means for varying the duration of the operating period of said timed mechanism and visual means comprising a third dial and a pointer indicating the duration of the operating period.

15. In a thermostatic switching mechanism, in combination, a bimetallic element, condition control mechanism operated by said element, a lever associated with said bimetallic element, said lever comprising two pivoted members, each provided with a cam follower, a pair of cams each adjacent one of said cam followers, a pair of dials, each fixedly associated with one of said cams, a pointer, indicia on said dials indicative of temperature values, rotation of said dials serving to vary the position of said cams in accordance with the temperature value adjacent said pointer, a timed mechanism, means associated with said timed mechanism to juxtapose one of said cam followers to its associated cam whereby the position of said lever and hence said bimetallic element is determined by one of said cams when said timed mechanism is operative and the other of said cams when said timed mechanism is inoperative in such manner that said element responds to one temperature for the duration of the period of operation of said timed mechanism and another temperature value subsequent to the termination thereof, and means for precluding the juxtaposition of one of said cam followers to its associated cam when the temperature value to which its dial is set is in excess of the temperature value to which the other dial is set.

16. In a device of the character described, in combination, a base, a support movably carried by said base, a thermostat mounted on said support, a switch actuated by said thermostat, means biasing said support to a first predetermined position, manual means for moving said support to a second predetermined position, timing means, operation of said manual means putting said timing means in operation and predetermined the time required for the timing means to return said support to its first predetermined position.

17. In a device of the character described, in combination, a base, a support movably carried

by said base, a thermostat mounted on said support, a switch actuated by said thermostat, means biasing said support to a first predetermined position, manual means for moving said support to a second predetermined position, timing means, operation of said manual means putting said timing means in operation and predetermined the time required for the timing means to return said support to its first predetermined position, and means for individually adjusting said predetermined positions.

18. In a device of the character described, in combination, a base, a support pivotally carried by said base, a thermostat mounted on said support, a switch actuated by said thermostat, means biasing said support to a first predetermined position, manual means for moving said support to a second predetermined position, timing means, operation of said manual means putting said timing means in operation and predetermined the time required for the timing means to return said support to its first predetermined position, a cover for said mechanism, means for adjusting one of said predetermined positions comprising a cam, and a dial for rotating said cam, part of said dial extending through a slot in the top of said cover so as to be capable of manual adjustment from outside of said cover.

19. In a device of the character described, a 30 thermostat, control means actuated thereby, said thermostat being movably mounted whereby the temperature at which its actuates said control means may be varied, a first resilient means biasing said thermostat to a first position, a second resilient means overpowering said first resilient means and biasing said thermostat to a second position, and means rendering said second resilient means inoperative for a predetermined period of time.

20. In a device of the character described, a 40 thermostat, control means actuated thereby, said thermostat being movably mounted whereby the temperature at which it actuates said control means may be varied, a first resilient means biasing said thermostat to a first position, a second resilient means overpowering said first resilient means and biasing said thermostat to a second position, means rendering said second resilient means inoperative for a predetermined period of time, and means for varying at least one of said positions.

21. In a device of the character described, a 50 thermostat, control means actuated thereby, said thermostat being movably mounted whereby the temperature at which it actuates said control means may be varied, a first resilient means biasing said thermostat to a first position, a second resilient means overpowering said first resilient means and biasing said thermostat to a second position, means rendering said second resilient means inoperative for a predetermined period of time, and means for varying said predetermined length of time.

22. In a device of the character described, in 60 combination, a condition responsive element, a control member actuated as a result of the response of said element to variations in the value of said condition, said condition responsive element being movable between first and second positions of adjustment, timing means operatively associated with said element for controlling its movement, said element occupying said first position when said timer is inoperative, and manual means for rendering said timing means 70 operative and causing said element to be moved

to said second predetermined position and at the same time predetermining the time required for the timing means to cause said element to be returned to said first predetermined position.

23. In a device of the character described, in combination, a condition responsive element, a control member actuated as a result of the response of said element to variations in the value of said condition, said condition responsive element being movable between first and second positions of adjustment, timing means operatively associated with said element for controlling its movement, said element occupying said first position when said timer is inoperative, manual means for rendering said timing means operative and causing said element to be moved to said second predetermined position and at the same time predetermining the time required for the timing means to cause said element to be returned to said first predetermined position, and manual means for varying at least one of said predetermined positions.

24. In a device of the character described, in combination, a base, a condition responsive element movably mounted on said base, a control

member mounted on said base and actuated as a result of the response of said element to variations in the value of said condition, said condition responsive element being movable between first and second positions of adjustment, timing means operatively associated with said element for controlling its movement, said element occupying said first position when said timer is inoperative, manual means for rendering said timing means operative and causing said element to be moved to said second predetermined position and at the same time predetermining the time required for the timing means to cause said element to be returned to said first predetermined position, manual means for varying at least one of said predetermined positions, a cover for said device, both of said manual means extending outside said cover, means for visually indicating the manual adjustment of said one of said predetermined positions, and means for visually indicating whether or not said timer is operative and if it is operative, how much time is required for it to cause said element to be returned to said first position.

CARL G. KRONMILLER.
